CLAIM

The ornamental design for a shoe, as shown and described.

DESCRIPTION

The file of this patent contains at least one drawing/photograph executed in color. Copies of this patent with color drawing(s)/photograph(s) will be provided by the Office upon request and payment of the necessary fee.

1. Shoe

1.1 : Front

1.2 : Back

1.3 : Left

1.4 : Right

1.5 : Top

1.6 : Bottom

1.7 : Perspective

The drawings only show the design on the left shoe; the right shoe is omitted as it is symmetrical to the left shoe; the reflection shown in the reproduction 1.6 is disclaimed.

1 Claim, 7 Drawing Sheets
